UNITED STATES PATENT OFFICE.

LOUIS WILLIAMS, OF DENVER, COLORADO.

DESIGN FOR A LOCK-HOOK.

42,987.

Specification for Design.

Patented Sept. 3, 1912.

Application filed February 6, 1912. Serial No. 675,878. Term of patent 14 years.

To all whom it may concern:

Be it known that I, LOUIS WILLIAMS, a citizen of the United States, residing at Denver, in the county of Denver and State of Colorado, have invented a new, original, and ornamental Design for Lock-Hooks, of which the following is a specification, reference being had to the accompanying drawing, forming part thereof.

In the drawing Figure 1 is a front elevation of a lock hook showing my new de-

sign; and, Fig. 2 is a side elevation of the same.

What I claim is:

The ornamental design for a lock hook as shown.

In testimony whereof I affix my signature in presence of two witnesses.

LOUIS WILLIAMS.
